UNITED STATES PATENT OFFICE.

SAMUEL I. PATTON, OF DALLAS, TEXAS, ASSIGNOR OF ONE-THIRD TO H. J. GARRETT,
OF DALLAS, TEXAS, AND ONE-THIRD TO T. J. BARTON, OF FORT WORTH, TEXAS.

WINDOW-SCREEN FASTENER.

Application filed March 13, 1924. Serial No. 699,049.

To all whom it may concern:

Be it known that I, SAMUEL I. PATTON, citizen of the United States of America, residing at Dallas, in the county of Dallas 5 and State of Texas, have invented certain new and useful Improvements in Window-Screen Fasteners, of which the following is a specification.

This invention relates to new and useful 10 improvements in window screen fasteners.

It is customary to hinge full-length window screens at the top and to swing the same outwardly at the bottom, when it is desired to open or remove the screen. Various 15 devices for fastening the bottom of the screen have been used such as hooks and eyes and hook bolts and pins. With such devices it is impossible to tightly fasten the screen or to draw the bottom of the screen 20 against the sill, particularly after the wood has swelled or contracted or the house has settled.

It is the object of my invention to provide 25 a fastener for securing the bottom of a hinged window screen firmly against the sill and having provision for compensating such irregularities as occur from varying thickness of wood, swelling, contracting and settling of the house.

A particular object is to provide a fastening 30 device comprising a fixed element secured to the window frame and a rocking element attached to the screen and having a wedging or cam action, when engaged 35 with the fixed element, whereby the screen is drawn tightly against the sill under varying conditions.

A further object is to provide a simple 40 fastener constructed to be readily and quickly installed and easily operated; and the parts of which may be inexpensively produced.

A construction designed to carry out the 45 invention will be hereinafter described together with other features of the invention.

The invention will be more readily understood from a reading of the following specification and by reference to the accompanying drawings, in which an example of the invention is shown, and wherein:

Fig. 1 is a partial inner element of a window frame and screen provided with a fastener constructed in accordance with my

invention, the fastener being disengaged and the screen free to swing open,

Fig. 2 is a similar view showing the 55 fastener engaged and the screen fastened,

Fig. 3 is a vertical sectional view on the line 3—3 of Fig. 1,

Fig. 4 is a cross-section on the line 4—4 of Fig. 1,

Fig. 5 is a perspective view of the pin, and

Fig. 6 is a perspective view of the latch.

In the drawings the numeral 10 designates the ear of a latch 11 and is bent at right angles from the central portion thereof. 65 The latch is provided with a curved finger 12 having its inner edge 13 inclined inwardly and offset from the ear. A curved handle 14 is provided on the opposite end of the latch.

This latch may be cast or stamped from sheet metal. The ear has a central eye 15 for receiving a screw 16, which latter is screwed into the inner face of the side rail A of a window screen, said screen being 75 hinged at its upper end in a suitable manner. The latch is left free to rotate around the screw.

A wedge pin or keeper 17 is driven into the side of the window frame B, against 80 which the screen closes. The pin is disposed horizontally and in juxtaposition to the latch, so that it is received between the finger 12 and the ear 10 when said latch is rotated to latch the screen. It will be seen 85 that when the latch is swung in a counter-clockwise direction, by moving the handle upwardly from the position shown in Fig. 1, the reduced end of the finger 12 engages 90 the inner side of the pin. As the swinging of the latch is continued, the inclined edge 13 rides over the edge of the wedge pin, whereby the screen is pulled inwardly by the lateral displacement of the wedge.

It is pointed out that the finger is curved 95 on an arc eccentric to the eye 15, the distance from the eye to the outer end of the finger being greater than the distance from the eye to the inner end of the finger. Consequently when the latch is swung, the edge 100 13 rides outwardly on the wedge pin and amplifies the lateral displacement of the latch, thus securely fastening the screen. The latched position is shown in Fig. 2, but

it is to be noted that this position may vary according to the distance the latch is swung to draw the rail A of the screen tight against the frame B. This provides for wear and distortion of the wooden parts.

The latch may be quickly placed by driving in the wedge pin with a hammer and setting the screw 16 with a screw driver. The latch is easily manipulated and is small and neat in appearance.

Various changes in the size and shape of the different parts, as well as modification and alterations may be made within the scope of the appended claims.

15. What I claim, is:

1. In a window screen latch, a rotatable latch member having a finger provided with an inclined edge and a wedge pin engaged

by said inclined edge when the latch is rotated.

2. In a window screen latch, a rotatable latch member having a curved finger provided with an inclined edge, and a driven wedge pin engaged by said inclined edge when the latch is rotated.

3. In a window screen latch, a rotatable latch member having a curved finger provided with an inclined edge, and a driven wedge pin engaged by said inclined edge when the latch is rotated, said finger being curved eccentrically to the pivot of the latch, whereby said inclined edge rides along the edge of the wedge pin as the latch is rotated.

In testimony whereof I affix my signature.

SAMUEL I. PATTON.
